UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

PANIC-BOLT.

1,345,041.

Specification of Letters Patent. Patented June 29, 1920.

Application filed December 8, 1917. Serial No. 206,323.

To all whom it may concern:

Be it known that I, HENRY G. VOIGHT, a citizen of the United States, residing in New Britain, county of Hartford, and State of Connecticut, have invented certain new and useful Improvements in Panic-Bolts, of which the following is a full, clear, and exact description.

This invention relates to emergency exit locks or so-called panic bolts of the type which are applied to the doors of school-houses, theaters, department stores and other buildings for facilitating exit where a fire or the like causes panic.

This invention refers more particularly to panic bolt mechanism in which the door is provided with bolts adapted to engage keepers or strike plates on the lintel and floor respectively and arranged to be released from said strike plates or keepers by means of a swinging cross-bar on the inner face of the door. The improved panic bolt is somewhat similar in some features to that described in my Patent No. 1,163,795, dated December 14, 1915, with the difference, however, that in the present case there are upper and lower sliding bolt members actuated in opposite directions respectively by the manipulation of the cross-bar. In the improved construction, as in the prior device, one of the bolt members has associated therewith a detent device for holding the bolts in retracted position automatically on the retraction of the bolts and for releasing the bolt members automatically when the door is closed.

The primary object of the present invention is to provide a panic bolt having improved and simplified means for actuating the bolts from the cross-bar whether the cross-bar is moved downward or upward. This increases to a considerable extent the scope and utility of the panic bolt because the door can be opened by pushing laterally or downward against the cross bar or by pulling the bar in an upward direction. In my improved construction, the connection between the cross-bar and the bolt or bolts is extremely simple and direct, and the cost of the panic bolt is therefore materially reduced. The construction and arrangement of the operating parts of the bolts are very

simple and inexpensive, while at the same time they are durable and efficient.

To these and other ends, the invention consists in the novel features and combinations of parts to be hereinafter described and claimed.

In the accompanying drawings:

Fig. 1 is an inside elevation of a door equipped with one form of my improved panic bolt, showing the door in its closed position;

Fig. 2 is an enlarged section on line 2—2 of Fig. 1, showing the casing in which one end of the cross-bar is mounted and in which the lower and upper portions respectively of the bolt members are housed, the cross-bar being in the normal position;

Fig. 3 is a view similar to Fig. 2 showing the bolt members retracted by the depression of the cross-bar;

Fig. 4 is a view similar to Fig. 3, showing the retraction of the bolt members by the raising of the cross-bar;

Fig. 5 is a rear view of the intermediate casing shown in Fig. 2, with the back plate removed, the bolt members and cross-bar being in the position shown in Figs. 1 and 2;

Fig. 6 is a transverse section through the intermediate or cross-bar casing;

Fig. 7 is a fragmentary view of the intermediate casing, looking from the inside of the room with the inside wall, viz., the outer casing wall, broken away to show the walking beam and spring, and

Fig. 8 is an enlarged fragmentary sectional view of a portion of the door and the floor, upon which the lower bolt and the cooperating strike plate are mounted.

Referring to the drawings, I have shown my improvements applied to a panic bolt mechanism embodying a bolt at the upper edge of the door for coöperating with a strike plate or keeper on the lintel, an oppositely acting bolt at the lower edge of the door coöperating with a strike or keeper in the floor, and a swinging cross-bar extending across the door and adapted to release the bolts when said cross-bar is moved either upward or downward relatively to its pivotal support or fulcrum. Both bolts are of the square headed type, and the upper bolt has associated therewith certain detent

mechanism for automatically holding the bolts retracted when they are released to open the door, and for releasing the bolt automatically when the door is closed again, 5 so that they thereupon take into their respective keepers. The bolt heads are of the sliding type and are actuated by the cross-bar in opposite directions, the lower bolt head being pulled up by operation of the 10 cross-bar simultaneously with the pulling down of the lower bolt. All of these features, however, are not essential parts of the invention.

The door A is mounted in a frame or 15 casing B, and is adapted to open outward, as usual in doors equipped with emergency exit locks or fasteners. The door swings directly over the floor C in the present instance, there being no threshold. A strike 20 plate or keeper 20 of customary form is mortised in the floor, as best shown in Fig. 8, and is adapted to be engaged by a sliding lower bolt member 21 having a square head 22 which engages the opening in the keeper 20. The bolt member 21 is guided vertically on the inner face of the door at 25 the lower portion thereof by a guide clip 23 applied to the lower inner face of the door by an attaching plate 24. In stating that the bolt head 22 is of the square headed 30 type, I mean to indicate that its lower end is at right angles to the axis instead of being beveled like a latch bolt. The sliding bolt member 21 extends upwardly approximately to the middle portion of the door, 35 and at its upper end it is secured to a part or extension 25 entering an intermediate casing D applied to the middle portion of the door near the free edge thereof. It 40 will be understood, of course, that the door is hinged at the right of Fig. 1, and that the bolt mechanism is arranged adjacent the left-hand edge. The bolt mechanism includes a swinging cross-bar E which is 45 pivoted to the door at one end of the bar, as shown at 26, and is pivoted to the casing 50 adjacent the other end of the cross-bar, as shown at 27. The cross-bar E is pivoted to the casing D between parallel lugs 28 55 extending integrally from the front wall of the casing. A pivot 29 for the cross-bar extends through the lugs 28 and through a portion adjacent the end of the cross-bar, a portion or finger 30 on the cross-bar extending beyond the pivot 29 within the 60 casing. The inner end of the extension 30 is rounded and is adapted to contact either with an abutment or lug 31 on the lower bolt member or a similar abutment or lug 32 on the upper bolt member. The outwardly extending portion of the sliding member 25 is formed as a sleeve 25^a having interior screw threads engaging screw threads on the upper extremity of the lower bolt rod. Within the case, the slide 25 is

offset and guided vertically in the casing, as shown in Fig. 5. It is held in place between the front wall 33 and the rear plate 34 of the casing, and it is also held in place between a side wall 35 of the casing and a guide lug 36. The abutment 31 on the slide projects laterally therefrom intermediate of the length of the slide. The upper bolt member comprises a slide 37 in the case D generally similar to the slide or extension 25. The upper end of the slide 37 has a sleeve 38, into which the lower end of the upper bolt rod 39 is screwed. The slide 37 is guided by the walls of the casing and by the guide lug 38', said slide being located at the 80 right-hand side of the casing and at the upper portion thereof, as shown in Fig. 5. The inner extremity of the cross-bar is interposed between the abutments 31, 32, and above the abutments 31, 32 the slides 85 25, 37 are interconnected by a walking beam 40 pivoted intermediate of its ends on a post 41 projecting from the front wall of the casing, and having slots 42 at the respective ends thereof engaging pins 43, 44 on 90 the respective slides. When the back plate 34 is held in the assembled position by a screw 45, the walking beam 40 will be properly held in place, and a spring 46 coiled about the post 41 and reacting at one end 95 47 against the walking beam and at the other end against a pin or projection 48 on the casing normally urges the walking beam in a clock-wise direction with respect to Fig. 5, so that the bolt members 21, 39 100 will be held normally in the protracted positions. When the cross-bar is swung downward from the position shown in Fig. 2 to that shown in Fig. 3, the slide 25 is carried upward by the engagement of the 105 extremity 30 with the lug 31, thereby pushing upward the lower bolt member, and the upper bolt member is simultaneously pulled downward through its connection with the upper bolt member by the walking beam, 110 whereby both bolts are simultaneously released. When, on the other hand, the cross-bar is swung upward from the position shown in Fig. 2 to that shown in Fig. 4, the extremity 30 of the lever engages the 115 lug 32 on the upper bolt member and pulls the upper bolt member downward in a direct manner, while the lower bolt member is pulled upward through its connection with the upper member through the walking 120 beam. The spring acting on the bolt mechanism normally holds the parts in the position shown in Fig. 5, with the lug 31 pressing down on the inner end of the cross-bar from above and the lug 32 pressing up on 125 the inner end of the cross-bar from beneath. In this position, the cross-bar is free to swing either up or down, and either movement will retract both bolts. Whether the bolts are released by either a downward 130

movement of the bar, as in Fig. 3 or an upward movement, as in Fig. 4, the spring acting on the walking beam tends to return the parts to the position shown in Figs. 2 and 5.

Adjacent the upper edge of the door A is mounted a rim casing 50 applied to the face of the door, and in this casing a bolt head is slidably mounted and is secured to the upper end of the bolt member 39. In the casing 50 a detent member (not shown) is preferably mounted to dog the upper bolt in its retracted position and this in turn dogs the lower bolt in its retracted position since the bolt members 21 and 39 are operatively connected together by the walking beam 40. The bolt mounted in the casing 50 co-operates with a strike plate or keeper 64 mounted upon the door frame, and this strike plate is preferably provided with a downwardly projecting finger 65 positioned to engage the detent mounted within the casing 50 to thereby release the bolt members 39, 21 as the door reaches its closed position. The construction and operation of the detent mechanism mounted within the casing 50 is clearly disclosed and claimed in my copending application Serial No. 262,659, filed November 15, 1918.

It will be understood that as the cross-bar E is either depressed or elevated, both bolt heads are simultaneously moved out of the respective keepers, and as the detent mechanism comes into play just as soon as the upper bolt is fully released and thereby locks both bolts in the retracted position, the bolt heads will not project beyond the upper and lower edges respectively of the door while the door remains open. More particularly, the lower bolt will be effectively held up from the floor so that it will not contact with or drag on the same, regardless of any pressure that may be put on the cross-bar while the door remains open. When the door is closed, however, the detent is automatically released by coming into contact with the depending finger 65 above mentioned. When the bolts are retracted by upward or downward pressure on the cross-bar, the door opens immediately, and when it is partially opened, the finger 65 is no longer in the way of the detent, and the latter is, therefore, free to move into locking engagement with the upper bolt under the influence of a spring.

It will be seen that by my invention the bolt mechanism may be released either by an upward or a downward movement of the cross-bar and at the same time the construction of the parts in the casing D is very simple, the cross-bar having a direct cooperation with both of the sliding bolt members.

Various changes may be made in the details of the construction without departure

from the scope of the invention as defined in the claims.

What I claim is:

1. In a panic bolt, a pair of oppositely moving sliding bolt members, an operating member adapted to be moved in one direction into direct coöperation with one of said members and to be moved in the opposite direction into direct coöperation with the other member, and a walking beam for operatively connecting said bolt members whereby the operation of one bolt member operates the other bolt member. 70

2. In a panic bolt, a pivoted operating bar having an operating projection located beyond the pivot, a pair of oppositely moving elements to be actuated having abutments between which said operating projection is interposed, and a rocking lever separate from said bar for operatively connecting said pair of elements. 80

3. In a panic bolt, a pair of sliding bolt members, a lever connection between said members, means movable in one direction to shift one of said members and movable in the other direction to shift the other member, said means including a pivoted bar having an operating projection, and abutments on the respective members disposed on opposite sides of said operating projection and positioned to be operatively engaged thereby. 90

4. In a panic bolt, a pair of oppositely moving bolt members having laterally extending abutments arranged in parallelism, an operating bar having an operating finger interposed between said abutments to operatively engage either abutment, and means independent of said abutments for imparting the movement of one bolt to the other. 100

5. In a panic bolt, a pair of oppositely moving bolt members having laterally extending abutments arranged in parallelism, an operating bar having an operating finger interposed between said abutments to operatively engage the same, said operating bar movable in one direction to operate one of said bolt members directly and movable in the opposite direction to operate the other member directly, and means independent of said operating bar for imparting the movement of one bolt to the other. 110

6. In a panic bolt, a pair of parallel bolt members each having an abutment projecting laterally toward the other member, said abutments being substantially parallel to each other, an operating bar, a pivot for said bar, and an operating extension on said bar beyond the pivot interposed between said abutments to operatively engage either abutment, and a walking beam operatively connecting said bolts. 120

7. In a panic bolt, a casing, a pair of sliding bolt members mounted in said casing, a walking beam connecting said members for movement in opposite directions, and 130

4

an operating lever pivoted to said casing and having direct engagement with one of said members when said lever is shifted in one direction, said lever having direct engagement with the other member when the lever is shifted in the other direction.

5 8. In a lock, a pair of sliding bolts arranged in parallelism and interconnected to move in opposite directions, and an operating member therefor separate from the interconnection between said bolts movable in either of two directions to retract said bolts and adapted to coöperate directly with either of said bolts.

10 15. 9. In a lock, a pair of sliding bolts, means interconnecting said bolts to move the same in opposite directions, a manually engageable operating member for said bolts movable in either of two directions to retract said bolts and adapted to coöperate directly with one of said bolts to move it in one direction and to coöperate directly with the other bolt to move it in the other direction.

15 20. 10. In a lock, a pair of sliding bolts arranged in parallelism, means interconnecting said bolts for imparting the movement of one bolt to the other bolt but in an opposite direction, and a manually engageable operating member for said bolts interposed between the same and movable in one direction to coöperate directly with one of said bolts and thereby actuate it in one direction, said operating member being movable in the other direction to coöperate directly with the other bolt and thereby shift it in a corresponding direction.

25 30. 35. 11. In a lock, a case, a pair of sliding members mounted therein in parallelism to each other, means connecting said members

for movement in opposite directions, and an operating member pivoted to one side of said case and having a portion interposed between said sliding members, said operating member being movable in either of two directions and adapted when moved in one direction to coöperate directly with one sliding member, and when moved in the opposite direction to coöperate with the other sliding member.

45 50. 12. In a panic bolt, a casing, a pair of oppositely moving, vertically sliding bolt members mounted therein, each bolt member provided with an abutment, said abutments positioned one above the other in substantially vertical alinement, an operating lever pivotally mounted upon said casing having a projection interposed between said abutments to retract one bolt member when moved in one direction, and to retract the other bolt member when moved in the opposite direction, and means for imparting the movement of one bolt to the other but in an opposite direction.

55 60. 65. 13. In a panic bolt, a pair of oppositely moving sliding bolt members, an abutment formed upon each of said members, a pivoted operating lever having an end interposed between said abutments, said end engaging one abutment to retract the bolt member upon which the same is formed when moved in one direction and engaging the other abutment to retract its bolt member when moved in the opposite direction, and means for imparting the movement of one bolt to the other.

70 75. In witness whereof I have hereunto set my hand on this 1st day of December, 1917.

HENRY G. VOIGHT.
